SOLVENT EXTRACTION OF OILS AND ACIDS

John D. Jenkins, Forest Hills, Pa., assignor to
 Pittsburgh Plate Glass Company, Allegheny
 County, Pa., a corporation of Pennsylvania

Application May 13, 1940, Serial No. 335,006

11 Claims. (Cl. 260—419)

The present invention relates to refining of glycerides of fatty acids and the free acids derived therefrom, and it has particular relation to the refinement by liquid phase extraction with a polar solvent of such glycerides and acids consisting of components which substantially differ from each other by reason of a difference in degree of unsaturation or activity of unsaturation, or in chain length of the molecule.

One object of the invention is to provide a process of removing a component from glycerides and free fatty acids of glycerides by extraction with a selective solvent, which process does not produce objectionable reactions that impair the value of one or more of the components of the material treated.

This and other objects of the invention will be apparent from consideration of the following specification and the appended claims.

In copending applications Serial No. 144,315, now issued as Patent 2,200,390 filed May 22, 1937 and 251,340, now issued as Patent 2,200,391 filed January 17, 1939, to Stephen E. Freeman are disclosed processes of separating glycerides and also free acids of glycerides into components by liquid phase extraction with furfural, furfuryl alcohol and other active or polar solvents, which include various activating groups such as OH, COO, NO₂, PO₄, and numerous other groups. These active solvents are found to have a substantially higher affinity for unsaturated glycerides and acids derived from such glycerides than for the more saturated or otherwise less active glycerides or acids. Correspondingly the more highly unsaturated or actively unsaturated glycerides and free acids thereof exhibit a substantially greater solubility in the solvents than the more completely saturated glycerides and acids or the unsaturated glycerides which by reason of the arrangement of groups are less active.

Under the provisions of the foregoing applications, oils and acids consisting of mixtures of more completely saturated and less completely saturated or actively unsaturated components are treated with an active or polar solvent to dissolve out a fraction enriched in the more unsaturated or actively unsaturated components and correspondingly to leave a raffinate of oil or acid which is enriched in the relatively highly saturated components, together with a certain amount of the active solvent dissolved therein. The mixture can then be separated into liquid phases, one consisting of the solvent and the fraction rich in unsaturates or active unsaturates and the other consisting of the more sat-

urated or less actively unsaturated material in which is dissolved a small amount of the solvent. These two liquid phases may be separated by appropriate means, and by distillation or other suitable treatment, the solvent may be removed therefrom, leaving the desired fractions of oils or acids.

Although it was thus possible to separate glyceride oils or the acids derived therefrom into fractions according to the degree or the molecular arrangement of unsaturation the unsaturated fraction did not always exhibit the characteristics desired in it, to the degree that might have been expected. For example, where the fraction was to be employed as a paint or varnish vehicle, it was often found that the extracted fraction dried slowly even though its iodine value was relatively high. Food products might be discolored.

It has now been discovered that this peculiar behavior is apparently due to some obscure chemical reactions within the oil or solvent or possibly between the two. It has further been discovered, that if an unsaturated glyceride or the free acids therefrom is extracted with a suitable selective polar solvent such as furfural, while it is blanketed or covered with an inert gas, such as carbon dioxide, flue gas, or nitrogen, the tendency is substantially eliminated. From this it may, perhaps, be deduced that the peculiar behavior of the extracted oil is in some way due to the action of atmospheric oxygen which is blanketed out or excluded by the inert medium covering the oil.

In the application of the principles of the invention various methods of extracting the oil with solvent may be employed. For example, extraction may be conducted as a simple batch operation by mixing the oil and solvent under a blanket of inert gas in a suitable container, then allowing the resultant fractions to separate into liquid layers and drawing off the layers into separate containers for removal of the solvent. However, the preferred method involves countercurrent extraction in columns in which all free surfaces of the glycerides or acids are protected by a blanket of inert gas. The gas may be almost any inert gas, such as carbon dioxide; however, nitrogen or nitrogen containing gases, such as flue gas, are preferred.

A suitable embodiment of apparatus for countercurrent extraction is illustrated in the accompanying drawing in which the single figure is a diagrammatical or schematic view of a suitable

embodiment of apparatus for use in practice of the invention.

In the drawing like numerals refer to like parts throughout.

The apparatus as disclosed includes an extraction tower or column 10 which may be packed with Raschig rings or Berl saddles, etc., and may be of substantially any diameter dependent upon the quantity of glycerides or acids to be passed therethrough. The height of the column preferably is approximately within the range of 30 to 50 feet. However, these limits may be substantially exceeded, if so desired. It also is provided with a cover or jacket 11, which, as shown, may be formed in separate sections, such as 12, 13 and 14, which may be of substantially any number dependent upon the gradation of temperature within the column which it may be desired to maintain. The sections may be supplied with heat exchange medium, such as water or the like through inlets 16 and outlets 17. The inlets may be connected to separate sources of heat exchange medium at different temperatures, or if preferred they may all be connected to a single source. Also, as shown in the drawings, the outlet conduit may be connected by a conduit 18 with the inlet conduit of the adjacent section. The various conduits are supplied with valves 19, which may be opened or closed to admit of the circulation of the heat exchange medium through each section of the jacket individually or to cause the fluid to flow from the outlet of one section to the inlet of the adjacent section as may be desired.

Glyceride oil or free acids of glyceride oils may be stored in a closed container 21, which, may be provided with a jacket 22 by means of which it may be maintained at any desired temperature. Oil from the container flows through conduit 23 and is forced by suitable pump 24 into an intermediate portion of the column 10, preferably at a distance of about 12 feet from the bottom of the column.

Solvent for the extraction may be stored in a container 25 and is fed through conduit 26 to a pump 27, connected to conduit 28 in a heater jacket 29, having at one extremity an inlet 31 for heated fluid such as water and at the opposite extremity an outlet 32 for the waste fluid. In some instances it may be desirable to add water or other fluid at least partially miscible with the solvent, but immiscible with the material to be refined, in order to reduce miscibility thereof in the solvent. Such addition may be made through conduit 32a. The upper extremity of conduit 28 discharges into the upper extremity of the column 10 at a short distance from the top thereof. Inert gas may, also, be supplied to container 25 through conduit 32b.

It will be apparent that by reason of the difference in specific gravity of the solvent and the glyceride oil or the acids derived therefrom the two liquids will tend to flow counter-currently with respect to each other. Assuming that the solvent is the heavier component it will descend while the undissolved oil will rise. Therefore, in a zone 33 extending approximately from the inlet for the solvent down some distance below the inlet for the glyceride oil or the acids, there will be a mixture of countercurrently flowing components. Also, the oil will be carried by the solvent a certain distance below the oil inlet. In the zone of countercurrent flow of selective solvent and oil or acid it will be apparent that there is very intimate contact, and the selective

solvent gradually extracts a fraction which is rich in the more soluble component, such as the more unsaturated or actively unsaturated glycerides and acids, or the glycerides or acids which are more soluble by reason of differences in chain length in the molecule. The less soluble components of the oil do not dissolve in the solvent, at least not completely but do tend to take up a certain amount of the solvent. In a zone near or slightly above the inlet for the conduit 28 the less soluble component or raffinate will collect as a body 36 of insoluble glyceride oil, or oil acid, which is free of the extract phase and which is saturated or substantially saturated with solvent and may be drawn off through a conduit 37, that leads to suitable apparatus (to be later described) for the separation of the solvent dissolved therein. Inert gas is admitted through conduit 37a to blanket the raffinate.

The undissolved solvent with the extract phase therein ultimately separates out in the bottom of the column as a distinct layer or fraction 39, which may be drawn off through a conduit 41, that extends upwardly a sufficient height to admit of hydrostatically balancing of the liquid therein against the liquid contained in the extraction column 10.

Since the solvent and the oils are of different specific gravity, and since under varying conditions there will be a tendency for the relative amounts thereof in the column 10 to vary somewhat, it is desirable to provide at the upper extremity of the conduit 41 a section 42 which can be elevated or lowered to accommodate for the variations, thus making it possible to assure that the various strata in the column 10 are approximately at the desired levels. The upper extremity of the adjustable section 42 is provided with a head 43, in which the pressure may be atmospheric. This head is filled with inert gas through conduit 43a.

The solvent charged with extract discharges through this head to a conduit 44 leading to the upper extremity of a flash vaporizing column 46, provided with a jacket 47 to which steam at a pressure of 20 or 30 pounds per square inch or other heat exchange medium may be admitted through conduit 48 and from which spent medium is discharged through conduit 49. The oil is delivered into column 46 as a shower or spray that falls into a spray trap 51 in which the droplets of separated oil, largely freed of the solvent, are collected. The column 46 preferably is maintained under partial vacuum, e. g. under a pressure of 100 or 300 m. m. Vaporization of solvent in the column is almost instantaneous. The solvent vapors pass off from the trap through conduit 52 to a condenser 53, which in turn discharges through conduit 54 and pump 56 back to the solvent container 25.

The extract separated from the vaporized solvent in the trap is discharged through conduit 57 to a surge tank 58, having inlet 59 for inert gas. From the latter, it, or any suitable portion thereof, is discharged through conduit 61 to stripping apparatus (to be described later) for removal of the last traces of the solvent contained therein. A portion of the extract with the small amount of solvent therein is discharged through conduit 62 to pump 63, which forces it through conduits 64 back into the column 10 at a point preferably below the feed oil inlet, but slightly above the upper limit of the separated solvent phase in the lower portion of the container. The concentra-

tion of the more soluble component is thus increased in a zone adjacent to solvent-extract layer and this results in the separation of more of the less soluble component from the oil so that ultimately an extract is obtained, which is richer in the more soluble component and poorer in the less soluble component, than would otherwise be obtained. Substantially any ratio of the extract, for example 10 to 90% of the extract may be recycled.

As previously stated the inlet for the recycled oil is slightly above the level of the separated solvent and preferably it is at such distance below the level of the inlet for the oil that the recycled oil, as it passes upwardly through the solvent, will reach approximately the same composition as the feed oil from the container 22. Assuming that furfural is employed as the selective solvent the distance between the inlets of the feed oil and the recycled oil may be approximately 12 feet. The distance between the inlets for the feed oil and the solvent may vary over a substantial range, but preferably is about 15 to 35 feet.

If preferred, separation of the extract from the solvent may be effected by addition of water, e. g. 3 to 15% of water or other non-solvent. The vaporizer 46 may then be eliminated or may be bypassed by conduit 65 interconnecting conduit 44 and conduit 57. Separation of the extract may be effected in the surge tank 58 by addition of water through conduit 65a.

The apparatus for removing the dissolved solvent from the raffinate includes a vaporizer column 66 into the upper extremity of which the conduit 37 discharges the raffinate as a spray. The column is provided with a heating packet 67, which is supplied with steam or other heated fluid by means of conduit 68 and the spent fluid is discharged from the jacket through conduit 69. The pressure within the column 66 like that in column 46 is subatmospheric—e. g., about 100 to 300 m. m. of mercury and evaporation of the most of the solvent is almost instantaneous. At its lower extremity the column discharges into a conventional spray trap 71, in which the droplets of raffinate from which much of the dissolved solvent has been evaporated are collected.

The solvent freed of raffinate and in vapor state is discharged through a conduit 72, to a line 73 leading to a condenser and source of vacuum (not shown). The raffinate, separated from the vapors in the trap 71 and still containing some solvent, is discharged through conduit 74 into the upper extremity of a stripping column 76, which column is provided with a jacket 77 supplied with steam or other heated fluid through conduits 78, having a connection to a supply line 79. Where steam is employed the pressure is preferably about 50 lbs. per square inch corresponding to about 280° F. The spent fluid is discharged from the bottom of the jacket through conduit 81.

Column 76 preferably is packed with an inert material such as Raschig rings, Berl saddles or other packing material designed to check the descent of the oil and to cause it to be spread out into thin films presenting large surfaces. Steam or other distilling medium is introduced at the bottom of the column through conduit 82 and passes upwardly through the packing in such manner as intimately to contact with the surface of the oil and thus to carry away any solvent dissolved therein. The steam or other medium passes out of the column more or less completely charged with solvent through conduit 83 and is

10 discharged into the line 72. The raffinate oil now freed of solvent is discharged through conduit 84 at the bottom of the column and is passed to storage or is passed on for further treatment, for example, for an additional extraction in further stages of apparatus. Such stages obviously may assume substantially the form of the apparatus herein disclosed and by such treatment it is possible to remove an additional fraction or fractions of more soluble component from the raffinate.

15 The conduit 61 carrying the more soluble or extract components of the glyceride oil or the acids thereof, namely the more unsaturated components, is discharged into a second stripping column 86 substantially corresponding in construction to the column 76 and having a jacket 87 for steam or other fluid as previously described in connection with the column 76. The column is also packed as indicated at 88 and is supplied with steam or inert gas through conduit 89. The steam or gas charged with solvent discharges from the upper extremity of the column through conduit 91, which also discharges into the vapor line 73 and passes on to suitable apparatus for separation of the solvent from the water vapors or gas. The component of the oil which initially is dissolved in the solvent and which is liberated in the column 86 is discharged 20 from the bottom of the latter through a conduit 92, is either passed to storage or is subjected to further treatment, for example, to further fractionation in additional stages of apparatus in order more completely to separate out any saturated or less soluble components which may be carried therein. In this way a fraction which is very rich in unsaturates or other component, which is selectively soluble in the solvent employed, may be obtained.

25 40 In the practice of the present invention substantially any of the selective solvents disclosed in the foregoing copending applications above referred to may be employed. Among such solvents are included furfural, above described, furfuryl alcohol, allyl alcohol, nitroethane, nitromethane, methyl formate, methyl levulinate, propionitrile, ethyl maleate, acetaldehyde, diacetyl, glycol diacetate, ethyl oxylate, methyl cellosolve acetate and others. The ratio of solvent to oil 30 may vary over a broad range extending for example of 1 to 1 all the way to 10 to 1.

35 45 The solvent system may include a solvent immiscible therewith, such as a paraffinic hydrocarbon having a boiling point above that of operation of the extraction system. Isooctane is a good example of such solvent. It may be used in a range of from about 1/2 to 5 parts for each part of polar solvent. It often assists in separating the less active components of the oil or acids by dissolving them out of the polar solvent.

50 55 60 65 70 Among the glyceride oils that may be fractionated are included bodied or unbodied linseed oil, marine oils, such as menhaden, sardine and whale oils, soya bean oil, perilla oil, cottonseed oil, corn oil, sunflower oil, peanut oil, olive oil, lard, tallow and the like. These oils comprise mixtures of glycerides of varying degrees of saturation and fractionation thereof is effected by the selective solvent by reason of the higher degree of solubility of the more unsaturated components in the selective solvent. The oils and free fatty acids may be deaerated prior to extraction, by heating them to 100° C. or thereabout and simultaneously subjecting them to vacuum.

or to blowing with nitrogen or other inert gas. The oils may be raw oils or may be alkali refined, or may be refined by other methods. They may, also, be bodied or unbodied.

It has also been found that certain of the oils, such as palm oil and coconut oil, which include in their compositions glycerides of fatty acids of varying chain length can similarly be separated into fractions, because of the greater solubility of the short chain acid glycerides in the selective solvent. For example, coconut oil which comprises essentially mixtures of glycerides of straight chain aliphatic acids of a chain length from 6 or 8 up to 18 or more may be separated into fractions which are greatly enriched in specific glycerides.

It is of course obvious that the apparatus and process as herein disclosed is also applicable to the fractionation of mixtures of relatively saturated and relatively unsaturated fatty acids derived from the oils herein disclosed.

Almost any inert gas, such as carbon dioxide, carbon monoxide, nitrogen, or a nitrogen containing gas such as flue gas may be employed as blanketing agents in the apparatus. Flue gas and nitrogen are of especial value because the solubility in glyceride oils is low.

The gases may be preliminarily dried in order to prevent hydrolysis of the solvent in the system. If the solvent does not tend to hydrolyze, such drying is not usually necessary. The inert gases not only prevent objectionable chemical reactions, but they also reduce fire hazards in the system, especially where immiscible hydrocarbons are present. They also help to reduce objectionable discoloration of the fractions obtained.

Under some conditions it may be possible to get substantially the same effects as obtained by blanketing the liquids in the apparatus by so constructing it as to exclude all contact of the fluids with air.

The extracted oils as obtained from linseed, soya bean, marine oils, perilla oil and others containing substantial amounts of glycerides susceptible of air drying are excellently adapted for use as drying oils in the fabrication of paints and varnishes. By application of the extraction process extracted oil having good drying properties and sufficiently free of objectionable matter, such as free acids, anti-oxidants break producing constituents, and the like can be obtained without subjecting the oil to severe treatment with acid or alkali. In the fabrication of paints and varnishes the conventional pigments, colors, thinners and the like are added as with conventional drying oils. For example, titanium oxide, lithopone and other pigments may be added in amounts of 5 to 90%. Turpentine or any other volatile thinner may be also added in an amount of 5 to 90%, more or less, based upon weight.

The forms of the invention herein disclosed constitute only a part of the possible applications of the invention. It will be apparent that numerous modifications can be made therein without departure from the spirit of the invention or the scope of the claims.

What I claim is:

1. A process of separating into components a mixture selected from a class consisting of a mixture of a plurality of glycerides and a mixture consisting of a plurality of fatty acids derived from said glycerides, said mixture including a component which is relatively difficultly soluble and a component which is rela-

tively more soluble in a furane compound, which process comprises providing a mixture of a furane compound and the material under a blanket of inert gas and then separating the mixture, into liquid phases, one comprising the furane compound saturated with the more soluble component and the other comprising the less soluble component saturated with the furane compound.

5 2. A process as defined in claim 1 in which the furane compound and mixture to be separated into components are flowed countercurrently in a tower and the liquid phases are collected respectively at the top and bottom of the column, separated by the intervening mixture of countercurrently flowing materials.

10 3. A process as defined in claim 1 in which the furane compound is furfural and the inert gas consists mainly of nitrogen.

20 4. A process of separating into components a mixture selected from a class consisting of a mixture of a plurality of glycerides and a mixture of a plurality of fatty acids derived from said glycerides, said mixtures each including a component which is relatively difficultly soluble and a component which is relatively more soluble in a furane compound, which process comprises countercurrently flowing a furane compound and the material to be separated into components in a tower, collecting as separate liquid phases a solution of the furane compound in the less soluble component and a solution of the more soluble component in the furane compound drawing off the latter phase through a stand-pipe balancing the liquids in the columns, the material in the column and the stand-pipe under a blanket of inert gas.

30 5. A process of separating into fractions a material selected from a class consisting of glyceride oils and free acids of said oils, one fraction being of a relatively high degree of saturation and a second fraction being of a relatively high degree of unsaturation, which process comprises contacting the mixture with a furane compound solvent for the unsaturated component which has relatively low solvent action for the more saturated component, to form two liquid phases, one of which comprises the first component saturated with the furane compound and the second of which is the furane compound saturated with the second component, said extraction being effected 35 in the absence of oxygen.

40 6. A process of separating into fractions a material selected from a class consisting of glyceride oils and free acids of said oils, one fraction being of a relatively high degree of saturation and a second fraction being of a relatively high degree of unsaturation, which process comprises contacting the mixture with furfural to form two liquid phases, one comprising the relatively saturated fraction having some furfural dissolved therein, the other comprising furfural in which is dissolved a relatively large amount of the unsaturated fraction, separating the two phases, removing the furfural therefrom and recycling the furfural for extraction of additional mixture, the furfural and the mixture being at all times excluded from contact with oxygen.

45 7. A process of separating into fractions a material selected from a class consisting of glyceride oils and free acids of said oils, one fraction being of a relatively high degree of saturation and a second fraction being of a relatively high degree of unsaturation, which process comprises contacting the mixture with furfural to form two liquid phases, one comprising the relatively saturated fraction having some furfural dissolved

therein, the other comprising furfural in which is dissolved a relatively large amount of the unsaturated fraction, separating the two phases, removing the furfural therefrom and recycling the furfural for extraction of additional mixture, the furfural and the mixture being at all times excluded from contact with oxygen, by blanketing them with an inert gas.

8. A process of separating into fractions a material selected from a class consisting of glyceride oils and free acids of said oils, one fraction being of a relatively high degree of saturation and a second fraction being of a relatively high degree of unsaturation, which process comprises contacting the mixture with furfural to form two liquid phases, one comprising the relatively saturated fraction having some furfural dissolved therein, the other comprising furfural in which

is dissolved a relatively large amount of the unsaturated fraction, separating the two phases, removing the furfural therefrom and recycling the furfural for extraction of additional mixture, the furfural and the mixture being at all times excluded from contact with oxygen, by blanketing them with a gas consisting mainly of free nitrogen.

9. A process as defined in claim 5 in which the solvent is furfural and the material treated is from a class consisting of soya bean oil, cotton-seed oil, coconut oil, and linseed oil.

10. A process as defined in claim 1 in which the solvent is further admixed with a hydrocarbon immiscible therewith.

11. A process as defined in claim 1 in which the material treated is preliminarily deaerated.

JOHN D. JENKINS.
